United States Patent Office

Des. 206,035
Patented Oct. 18, 1966

206,035

JET AIRCRAFT

John E. Steiner, Bellevue, and Joseph F. Sutter, Seattle,
Wash., assignors to The Boeing Company, Seattle,
Wash., a corporation of Delaware

Filed June 22, 1965, Ser. No. 85,848

Term of patent 14 years

(Cl. D71—1)

Fig. 1.

Fig. 2.

Fig. 3.

Fig. 4.

Fig. 5.

FIG. 1 is a perspective view from above and forward of the aircraft of our new design;

FIG. 2 is a perspective view from below and aft of the aircraft of FIG. 1;

FIG. 3 is a side view of a modified form of the aircraft shown in FIG. 1;

FIG. 4 is a top view of the aircraft of FIG. 3; and

FIG. 5 is a front view of the aircraft of FIG. 3.

The dominant features of our design reside in those portions shown in full lines.

We claim:

The ornamental design for a jet aircraft, as shown and described.
